CLAIM

The ornamental design for a portion of headlight for a vehicle, as shown and described.

DESCRIPTION

FIG. 1 is a front elevational view of a portion of headlight for a vehicle, showing our design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a top and right front perspective view thereof; and,

FIG. 8 is a bottom and right front perspective view thereof. The broken lines in the drawings illustrate portions of the portion of headlight for a vehicle which forms no part of the claimed design.
